UNITED STATES PATENT OFFICE.

PAUL EVETTE, OF PARIS, FRANCE.

CLARINET.

SPECIFICATION forming part of Letters Patent No. 729,309, dated May 26, 1903.

Application filed December 30, 1902. Serial No. 137,172. (No model.)

To all whom it may concern:

Be it known that I, PAUL EVETTE, engineer, a citizen of the French Republic, residing at Paris, France, (and having post-office address 5 18 and 20 Passage du Grand Cerf, in said city,) have invented certain new and useful Improvements in Clarinets, of which the following is a specification.

This invention has for its object an improvement in clarinets, permitting to act on the keys for trilling the keys A-natural and the key G-sharp with the forefinger of the right hand.

In order that this invention may be clearly understood, I shall describe it with reference to the accompanying drawings, of which—

Figure 1 is a view of a part of a clarinet of the Boehm's system, for instance, having the said improvement. Fig. 2 is a partial section 20 of this clarinet, and Fig. 3 is a detail.

In the clarinets of the Boehm's system the key A-natural is trilled by opening simultaneously the keys *a* and *b* by means of a finger-piece *c* and the key G-sharp is trilled by 25 opening only the key *b* by means of a finger-piece *d*.

In order to set the keys *a* and *b* with the forefinger of the right hand, I have devised the following dispositions: The simple heads 30 *e f* are made double, as shown at *e' f'*. In the heads *e' f'* a rod *g* is mounted loose and rotates in these bearings *e' f'*. This rod *g* is provided at its upper end with an arm *h* and at its lower end with a bent lever ended by 35 a finger-piece *i*. Concentrically to the rod *g* and somewhat shorter is a hollow rod *j*, rotating on the rod *g* and provided at its upper end with an arm *k* and at its lower end with a bent lever ended by a finger-piece *m*. The 40 finger-piece *c* is provided with a projection *n*, on which bears the end of the arm *k*. A short arm *o* is fitted to the rod of the key *b* and is, in connection with the lever *p*, pivotally mounted on *q*, the arm *h* bearing on the 45 other arm of the said lever *p*.

In order to act on the keys for trilling the A-natural with the forefinger of the right hand, the operator acts with the said forefinger on the finger-piece *m*. The hollow rod 50 *j* rotates around the rod *g*. The arm *k* bears on the projection *n* of the finger-piece *c* and

presses the said finger-piece *c*, trilling simultaneously the key *a* and the key *b*.

In order to act on the key G-sharp with the forefinger of the right hand, the operator acts 55 on the finger-piece *i*, and thus the rod *g* is rotated in the hollow rod *j*, the arm *h* bearing on the lever *p*, which oscillates on its pivot *q* and raises the short arm *o*, thus trilling the key G-sharp. 60

It is well understood that the finger-pieces may have different forms and dispositions.

This disposition may be used for other clarinets than those of Boehm's system. For instance, it may be used on the clarinets with 65 thirteen keys.

Having now particularly described my invention and in what manner the same may be performed, I declare that what I claim is—

1. In a clarinet an improvement for acting 70 on the key G-sharp with the forefinger of the right hand, consisting in a rod *g*, two heads *e' f'* in which the said rod rotates, a finger-piece *i* provided at the lower end of the said rod, an arm *h* provided at the upper end of 75 the said rod, a lever *p* brought in action by the said arm *h* and an arm *o* fitted on the rod of the key G-sharp in connection with the said lever *p*, substantially as described.

2. In a clarinet an improvement for acting 80 on key G-sharp and the key A-natural with the forefinger of the right hand, consisting in a rod *g*, two heads *e' f'* in which the said rod rotates, a finger-piece *i* provided at the lower end of the said rod, an arm *h* provided 85 at the upper end of the said rod, a lever *p* brought in action by the said arm *h* and an arm *o* fitted on the rod of the key G-sharp in connection with the said lever *p*, a hollow rod *j* concentrically surrounding the rod *g*, a finger-piece *m* at the lower end of the said rod 90 *j*, an arm *k* at the upper end of the said rod *j*, a projection *n* of the finger-piece *c* in connection with the said arm *k*, substantially as described. 95

In testimony whereof I have hereunto set my hand in presence of two subscribing witnesses.

PAUL EVETTE.
